COKING RETORT

Harold R. Horner and Richard J. Hennessy, Indianapolis, Ind., assignors to Reilly Tar and Chemical Corporation, Indianapolis, Ind., a corporation of Indiana

Application June 26, 1947, Serial No. 757,286

11 Claims. (Cl. 202—124)

1

This invention relates to the art of coking carbonaceous materials, including pitches and coal, and involves an unique retort structure wherein the materials are heated indirectly up to coking thereof, and thereafter may be heated directly to increase the density of the coke to as high as 2.07. By use of our invention, the retort is employed as a still to drive off and recover gases and condensable volatiles from the carbonaceous materials. To do so, the retort is equipped with a plurality of vertically disposed metal tubes spaced through the carbonaceous material, and it is through these tubes that the heating medium is directed entirely removed from communication with the space in which the material is charged. By use of the tubes, the material may be carbonized or coked at temperatures up to 1400° F., to produce "soft" coke, but to calcine to produce a hard, dense coke, requiring temperatures from 1800 to 2700° F., the tubes are designed to permit withdrawal so that the coke may be heated directly and above the temperatures which the tubes may withstand.

While the invention contemplates coking of coals as well as of pitches, the description of the one form of the invention herein set forth, will be directed mainly to the operations for coking pitches, since such material is in a liquid state in the retort before reaching its initial coking temperature, and the invention includes the structure and method of handling the liquid state of the pitch, as well as the plastic state through which coal passes to the coked state.

The invention further provides that following the completion of the coking operation, the coke produced may be withdrawn from the retort simply by dropping it therefrom under the influence of gravity. It is therefore a primary purpose of the invention to produce a highly uniform coke product not only in respect to the cellular structure but also in respect to the chemical constituency and purity.

Further primary objects of the invention reside in the particular combination of elements employed to produce a relatively simple mechanical structure for carrying out the process of the invention, and in the simplicity of operation as well as the long life thereof.

These and many other objects and advantages of the invention will become apparent to those versed in the art in the following description of one particular form of the apparatus embodied in the invention, as illustrated more or less diagrammatically in the accompanying drawings, in which

2

Fig. 1 is a view in side elevation of a structure embodying the invention;

Fig. 2, a view in longitudinal, vertical section through the retort only with a limited number of flues in position;

Fig. 3, a detail in vertical section on an enlarged scale through the retort floor sealing means;

Fig. 4, a view in top plan of the structure with half of the flues in position and the upper structural iron work removed;

Fig. 5, a detail in side elevation on an enlarged scale of a corner of the retort floor supporting construction;

Fig. 6, a top plan view of that portion of the structure included in Fig. 5;

Fig. 7, a vertical transverse section on the line 7—7 in Fig. 6;

Fig. 8, a vertical transverse section through the retort on the line 8—8 in Fig. 4;

Fig. 9, a view in rear end elevation of the structure shown in Fig. 1;

Fig. 10, a detail in vertical section through the upper flue thimble and sealing means, on an enlarged scale;

Fig. 11, a detail on an enlarged scale in end elevation of the flue traveling carrier track;

Fig. 12, a detail in vertical section through the retort indicating the flue assembly therewith;

Fig. 13, a detail in vertical transverse section on an enlarged scale through a retort door carrying roller mounting;

Fig. 14, a view on an enlarged scale in transverse section on the line 14—14 in Fig. 12;

Fig. 15, a central vertical section on the line 15—15 in Fig. 14;

Fig. 16, a view in front elevation of the floor shifting drive mechanism; and

Fig. 17, a view in vertical section on the line 17—17 in Fig. 16.

Referring to the drawings, in which like characters of reference indicate like parts throughout the several views, a suitable framework is provided, herein shown as comprising structural steel members wherein there are five I-beam columns 20, 21, 22, 23, and 24 in parallel vertical alignment on one side and 25, 26, 27, 28, and 29 in vertical alignment on the other side. These two sets of vertically disposed columns are spaced apart a sufficient distance to permit the desired width of retort generally designated by the numeral 30 to be carried therebetween and supported thereby. These columns in each set are interconnected by horizontally disposed members 31 with diagonal braces 33 all so provided and

interconnected as to produce a substantially rigid framework. The end columns 24 and 29 are also tied together to maintain the parallel alignment of the two sets of columns by horizontally disposed members 34 and diagonal braces 35, the exact dispositions of which do not enter into the invention per se. In any event, the space between the two sets of columns and the side and end interconnections is left clear and free of obstruction to permit the mounting of the retort 30 therebetween and for other reasons that will hereinafter become apparent.

Mounted between the columns 22, 23, and 24 on the one side, and 27, 28, and 29 on the other side, is the retort 30 which is essentially a box-like structure with an interiorly presented wall and ceiling surface of refractory material. In this regard, the side walls 36 and 37, and the front and rear end walls 38 and 39 respectively are formed in place within an outer metallic shell 40, to have the side and walls flare outwardly from top to bottom by their interior surfaces. The retort ceiling 41 is formed to have its sides and ends to be substantially integral with the side and end walls and is supported in any suitable manner such as by the angle irons 42 carried horizontally across the retort under and connected preferably in an expansible manner (not shown) to transversely positioned channels 43 secured respectively to their ends to the horizontally and longitudinally disposed I-beams 44, 45 secured on the one side between the columns 22, 23 and 23, 24, and the I-beams 46 and 47 secured similarly between the columns 27, 28 and 28, 29 on the other side. The lower ends of the retort walls are supported on structural posts 48 and 49, Fig. 8, set upright against and secured to the inner faces of the respective columns 22, 23, and 24 on the one side and 27, 28, and 29 on the other side, the exact details of such support not entering per se into the present invention. However, in the present form, such support includes the member 50 which completely encircles the lower outside end portion of the retort side and end walls. Against the under side of that member 50 is secured a face plate 51.

A refractory floor 52 is formed and carried in such manner that it may be raised and lowered under control to form a closure across the under side of the side and end walls 36, 37 and 38, 39. This floor 52 is built up over a steel plate 53 in turn carried by a plurality of transversely positioned I-beams 54. Extending entirely around the refractory floor portion 52 is a vertically disposed metallic wall 55 on the upper portion of which is secured an outwardly extending grooved member 56.

In order that the retort 30 may carry liquified material therein, it is necessary that some sealing means be provided between the floor 52 and the walls of the retort. In the present form of the invention, it is contemplated that this sealing means consist of one or more ribs bearing compressively against resilient packing material in such manner that following the coking operation, the floor may be lowered to break that seal without difficulty. In the present form of the invention, there is a single rib 57 provided to extend downwardly from the plate 51 entirely therearound to enter within the groove 58 of the member 56, Fig. 3. This rib 57 may have a knife edge for better sealing under low pressure, but where sufficient power is available to lift and hold up the floor 52, the rectangular form of the rib operates satisfactorily. Incidentally, the member

56 is maintained against bending downwardly by means of a plurality of spacer plates 59 fixed between the under side of the member 56 and the top side of the plate 53 which is extended outwardly beyond the metal wall 55.

The floor supporting beams 54 have their ends supported on the one side across the tops of the spaced apart channel irons, 60, 61 and their opposite ends on the tops of the spaced apart channels 62, 63. The channels 60 and 62 have rotatably mounted therebetween a plurality of flanged wheels 64, herein shown as three in number, to ride on the rail 65 in turn fixed to the top side of a horizontally disposed I-beam 66. Similarly, a plurality of flanged wheels 67, herein shown as three in number, are rotatably mounted between the I-beams 62, 63 to roll on the track 68 in turn fixed to the top side of the horizontally disposed I-beam 69.

20 The I-beams 66 and 69 are supported each by a plurality of hydraulically operated jacks 70. In the form herein indicated, Figs. 2, 8, and 9, these jacks 70 are supported by brackets 71 fixed to the respective posts 48 and 49. The shiftable jack heads 72 bear against the under sides of the beams 66 and 69 whereby these beams may be raised and lowered in accordance with the operation of the jacks. To prevent lateral movement beyond the permissible limits, the I-beams 66 and 30 69 in each instance carry guide plates, Fig. 8, 73 and 74 to extend from the beam and onto each side of the respective posts 48 and 49, these plates 73 and 74 carrying one or more (herein shown as two) spacer plates 75 which extend horizontally 35 outwardly from the beams to bear against the inner faces of the respective posts 48 and 49.

In view of the floor sealing means above indicated, it is necessary to lower the floor 52 to permit moving of the floor from under the retort 30, and this is accomplished by releasing the jacks 70. Furthermore, it is necessary to shift the floor 52 to one side of the retort in order to permit release of the coked materials therein so that such materials may fall from the retort.

45 Now in order to permit this travel of the floor from under the retort, tracks 76 and 77 are mounted at fixed elevations in alignment vertically with the rails 65 and 68, but at lower elevations than those of the rails 65 and 68 when the floor 52 is in its uppermost, sealed position against the under side of the retort 30. In other words, the rails 76 and 77 are so positioned that they will be in horizontal alignment with the rails 65 and 68 when that floor 52 has been lowered to a predetermined position permitting it to be pulled from under the retort. In the form herein shown, these rails 76 and 77 are secured to the upper sides of I-beams 78 and 79 in turn supported by transversely positioned beams 80, in turn supported by their ends by longitudinally disposed members 81 secured to the inner sides of the respective vertical columns 20, 21, 22 on the one side and 25, 26, and 27 on the other side.

65 At the front end of and ahead of the foremost wheels 64 and 67, the wheel carrying channels, 61 and 62, are interconnected respectively by a front channel 82 and a rearwardly spaced channel 83. Then suspended from the under 70 sides of these channels 82 and 83 are a pair of spaced apart plates 84, 85 on the one side, and 86, 87 on the other side, Fig. 8. Between the lower ends of these respective plates is secured a short length of an I-beam 88 with its web horizontally disposed, and then the plates in each

instance are further secured one to the other and braced by fixing the ends thereto of the vertically disposed plates 89 and 90.

The forward end of this beam 88 is caused to extend forwardly of the front ends of the plates 84, 85 and 86, 87 respectively a sufficient distance to fixedly carry through its web a vertically disposed thimble 91. The under sides of the flanges of the beam 88 are cut away, Fig. 5, up to the under side of the web from the front end of the beam throughout a major length of the extending portion thereof.

Horizontally disposed angle irons 92 and 93 are fixed respectively along the inner faces of the webs of the I-beams 78 and 79 to support slidably thereon the ends of an I-beam 94 which, in the present showing, has its web horizontally disposed. Each end of this beam 94 is provided with shoes 95 and 96 respectively to slide along on the angle bars 92 and 93. These shoes may take any desired shape, being herein shown as substantially half-round bars with their flat sides undermost and their upper rounded sides bolted in half round sockets in the beam 94. The beam 94 is provided with open end, vertically disposed sleeves 97 and 98, respectively spaced apart longitudinally of the beam 94 so that their axes may come into alignment with the respective axes of the thimbles 91 carried in the ends of the beams 88 upon suitable shifting of the beam 94 thereunder. In this regard, the angle irons 92 and 93 are so disposed vertically along the faces of the beams 78 and 79 that the beam 94 may be shifted under the forward ends of the beams 88 with some clearance between the lower ends of the thimbles 91 and the upper ends of the sleeves 97 and 98. Coupling pins 99 and 100 are respectively dropped down through the thimbles 91 to extend therefrom into the respective sleeves 97 and 98 brought thereunder. The coupling pins 99 and 100 are fixed in the present showing against dropping on through the thimbles 91 by means of heads 101 carried on the upper ends of the pins to strike against the top ends of the thimbles. By reason of the employment of this coupling means, the retort door 52 may be lowered and raised in respect to the beam 94 which maintains a fixed elevation by its end bearings on the angle irons 92 and 93, thereby maintaining the coupling engagement by means of the coupling pins 99 and 100 sliding vertically in the sleeves 97 and 98, these pins being sufficiently long so as to remain engaged within the sleeves throughout the limit of vertical travel of the door 52.

As above indicated, the floor or door 52 is required to be shifted horizontally from under the retort 30 in order to dump coke therefrom. Now to effect horizontal travel of the door 52, some pulling means is supplied to hitch to the beam 94 to pull it forwardly and rearwardly. One such means is herein shown. In this means, there is a chain 102 on the one side of the apparatus (left hand side) which has one end secured to the forward side of the beam 94 to be carried therefrom substantially horizontally, forwardly to wrap around and under a pulley 103 which is rotatably mounted on a fixed horizontal axis inside of the column 20. From the under side of the pulley 103, the chain 102 extends horizontally rearwardly to wrap over a pulley 104 and downwardly and under a drive sprocket 105 to continue therearound and up over a pulley 106 and thence substantially horizontally rearwardly around and over a pulley 107

rotatably carried on a horizontal shaft 108 which is located back, inside of the column 20. From the top side of the pulley 107, the chain 102 is carried forwardly to be attached to the rear side of the beam 94. In the same manner, a chain 109 is mounted in alignment with the sleeve 98 toward the other end of the beam 94 to have its respective ends attached to the forward and rear side of the beam 94. The shaft 110 on which the sprocket 105 is fixed is carried horizontally across to have another driving sprocket 111 fixed thereto around which the chain 109 engages. A chain driving motor 112 is mounted suitably to drive through a gear reduction box 113 a sprocket 114 which drives a chain 115 that extends around a sprocket 116 fixed to the shaft 110. The shaft 105 is preferably mounted substantially midway of the shafts of the pulleys 103 and 107. By energizing the motor 112, the door 52, after being lowered from the sealing position against the retort, may be pulled forwardly to a position entirely removed from the under side of the retort 30.

The retort ceiling 41 which hangs from under the transverse beams 43 has sufficient vertical thickness to prevent appreciable transfer of heat from the inside to the outside of the retort. Furthermore, the outer top side of the ceiling member 41 is preferably protected against the elements by any suitable means such as by the herein shown metallic deck 117 which unites by its edges with the retort surrounding shell 40. A plurality of thimbles 118 are provided to extend through the ceiling member 41 and upwardly through the deck 117. The number of these thimbles will depend upon the horizontal sectional area of the retort 30. They are spaced apart, vertical center from vertical center, a suitable distance both longitudinally and laterally of the retort to locate heat flues or tubes through the retort to obtain the desired distribution and conduction of heat therefrom through the mass of material to be coked within the retort, all as will be more fully described later herein. One particular spacing arrangement of these thimbles which has been found to be successful, and without limitation of the invention thereto is two feet both longitudinally and laterally. In the present form of the invention, there are five of these thimbles spaced apart laterally of the retort in ten rows thereof longitudinally of the retort. This, of course, is merely illustrative of one permissible construction.

55 Where the retort is to be charged solely with a liquid material such as pitch, these thimbles may be of constant diameter throughout their vertical lengths, but where the retort is to be used for materials that may be charged either 60 in solid masses or in liquid form, it is preferable that these thimbles be formed to have their upper ends flaring outwardly to a diameter larger at the roof end than the diameter at the inner ceiling end so that the thimbles in each instance 65 serve somewhat as funnels. Moreover, the flared type of thimble as herein illustrated lends itself to a better seal against the escape of gases or vapors outwardly through the thimbles.

The floor 52 is provided with a plurality of 70 circular openings 119 therethrough to be axially in alignment with the thimbles 118 when the floor 52 is in the closed position under the retort 30. That is, there are as many floor holes 119 as there are thimbles 118 above. Referring 75 primarily to Figs. 12, 14, and 15, these holes 119

are defined by passageways flaring outwardly and upwardly to a top diameter exceeding the diameter at the under side of the floor. The upper end of each passageway 119 at least is provided with a metallic inserted collar 120. The upper edge of the collar 120 is placed in a plane substantially parallel to the top face of the floor 52 at a slight distance therebelow to provide an annular shoulder therearound. Preferably, the floor 52 is recessed radially outwardly from the top face of the collar 120 to provide additional space for the insertion of a gasket 121 over the top edge of the collar 120.

Flue tubes 122 are provided in number equal to the number of thimbles 118. These tubes 122 are preferably made out of some material that at least will not deteriorate too rapidly under oxidizing effects of the temperatures required within the tubes while surrounded by such materials as pitch when the coal is being coked. The so-called "stainless" steels constitute one variety of material suitable for fabricating these tubes 122 when coal is being coked.

Each tube 122 is made to have a diameter such that the lower end of the tube may be supported from the top edge of the collar 120, and have its internal diameter at its lower end substantially equal to the internal diameter of the collar 120. Some centering means is employed to facilitate the positioning of the tube 122 in each instance in axial alignment over the collar 120 and to prevent lateral displacement therefrom when the tube is in use as a flue. In the present form of construction herein shown, such centering means comprises a collar 123 fixed inside of the lower end of the tube 122 to extend downwardly therefrom by a short length. Extending downwardly and inwardly from this collar 123 are a plurality of guiding ears 124, herein shown as four in number, Fig. 14. This arrangement permits the tube 122 to be lowered through a thimble 118 to have the lower end of the tube approach the collar 120 and to be centered therewith by the entrance of the ears 124 therewithin, and finally, to have the tube collar 123 enter within the upper portion of the floor collar 120 to have the lower end of the tube 122 sit on the gasket 121. In practice, this gasket 121 may consist of asbestos yarn initially held in place by sodium silicate, this yarn being compressible and compacted to a sealed condition by pressure exerted thereon from the weight of the tube 122 as it is allowed to rest on the gasket.

While it is entirely feasible to have the entire length of the tube 122 of constant diameter, it is desirable, in using the flared style of thimble 118 as herein shown and described, to reduce the diameter of that portion of the tube 122 to permit sufficient clearance around that reduced length and the smaller diameter portion of the thimble 118 to permit passage therearound into the retort of solid particles of material to be coked, such as coal or broken up chunks of pitch. In the present showing, the tube 122 in each instance is provided with a reduced diameter length 126. The length of this portion 126 is sufficient to have the juncture between it and the major length of the tube 122 of the larger diameter to come below the under side of the thimble 118, Fig. 12, when the tube 122 is in its normal, seated position, as best indicated in Fig. 12, and the top end of the length 126 is substantially at the level of the top of the thimble 118.

Since it becomes necessary to withdraw the tubes 122 from the retort following the coking

operation, some means is provided for engaging the upper ends of the tubes. In the form herein shown, Figs. 10 and 12, the upper end of the length 126 is provided with diametrically spaced apart holes 127 and 128 so that a clevis 129 may be positioned over the top end of the length 126 to straddle that end in such manner that a pin 130 may be inserted through those holes and the clevis 129.

Normally, all of the tubes 122 rest by their own weight free of any other vertical support to bear by their lower ends directly upon the gaskets 121 as before described. In order to hold the tube length 126 in its central position through the thimble 118, a number of arms 131, herein shown as four in number are fixed to each tube length 126 to extend radially therefrom and bear by their outer ends (at the time of charging the retort) against the flared wall portion of the thimble 118.

Sealing means is provided between the thimble 118 in each instance and the tube length 126. As indicated in Fig. 10, the thimble 118 is provided with an inwardly and upwardly turned flange 132 around the major diameter portion of the thimble 118 so as to provide a groove 133 the earound open from the upper side of the flange. The internal diameter of this flange 132 is sufficient to permit the arms 131 to pass freely therethrough. Within this groove 133, there is carried any suitable sealing means 134 such as asbestos yarn, or even some plastic cement as may be preferred. A closure plate 135, circular in shape, is provided with an outer downwardly turned lip 136. The central portion of the member 135 is provided with an opening 137 so as to slidily receive the upper end of the tube length 126 therethrough. Then spaced radially outwardly from the margin of this opening 137 is an upwardly extending flange 138 fixed to the member 135 so as to provide a packing groove or channel between the flange 138 and the side of the tube length 126 of sufficient width to receive therein suitable sealing packing 139 of a fibrous or cementitious nature as may be most suitable.

The plate or lid 135 is covered over with coke fines. The tubes 122 will expand vertically when heated, and these upper lengths 123 will travel slidily through the opening 137 with the packing 139 effectively providing a gas seal there-around.

At regular intervals, a plurality of girders 140 are provided to extend between and interconnect the inside beams 61 and 62 in the floor construction. In the form herein shown, Fig. 2, ten of these cross girders 140 are provided, arranged in pairs and are shown as having the form of channel irons. There are secured to these cross girders 140, burners 141, each burner being arranged in axial alignment with a passageway 119 through the floor 52 thereabove. The burners 141 are preferably fixed in position to the girders. While such burners may be adapted to burn oil, in the present showing, they are intended to burn gas. All of the burners are connected with suitable gas supply lines 142, Fig. 12, the exact details of the piping connections thereof being omitted for the sake of clarity in showing the general structural arrangement, inasmuch as such piping does not enter into the invention per se. It is sufficient to note that each burner 141 is supplied with a pilot burner or a lighting burner 143 adjacent the upper end thereof, and that all burners may be individually regulated by 75 a controlled valve 144 adjacent thereto. Fur-

thermore, since the burners 141 are fixed relative to the floor 52 to travel therewith, a suitable quick detachable connection is required to interconnect the outside gas feed main with the general piping system 142, such connection not being herein shown since it is within the skill of the ordinary mechanic to make that connection which is not immediately a part of the invention as to its specific details.

A pitch supply pipe line 143 is provided to convey the liquid pitch from any suitable supply source to enter through the top of the retort 30, Fig. 8. In order to permit escape of and to take off vapors and gases from the retort, outlet pipes 144, herein shown as two in number, lead diagonally upwardly and outwardly through the upper corner of the retort 30 and thence downwardly into a collecting manifold 145 which may lead to any suitable destination as may be desired, such as through a scrubber or a gas collecting tank. Obviously, a slight vacuum may be produced in the manifold 145 if such be desired to induce a flow from the retort.

The structural framework above described is extended above the retort level by the columns 20, 21, 22, 23, and 24 on the one side and 26, 27, 28, and 29 on the other side vertically to carry at its top side a traveling crane employed to raise and lower the flue tubes 122 in respect to the retort 30 and also to carry them to one side thereof. In the form herein shown, runways 146 and 147, Fig. 9, are carried in parallel, fore and aft positions across the structural framework inside of the columns just enumerated. A bridge 148 is carried by these runways 146 and 147 to be shiftable therealong. The bridge 148 carries the hoist mechanism 149 which may be shifted along the bridge 148 through the trolley wheels 150. A cab'e 151 drops from the hoist 149 to carry the block 152 which in turn engages centrally with a yoke 153, the yoke herein being shown as a length of an I-beam. Suspended from the under side of the yoke 153 are a plurality of rods 154, one spaced from the other a distance equal to the spacing apart of the axes of the flue tubes 122. The number of these rods 154 hanging from the yoke 153 equals the number of tubes 122 in a transverse row across the retort 30, five in the present showing. Each rod 154 carries a hook 155 in turn carrying the clevis 129 to straddle the upper end of the tube length 126 and be engaged therewith by means of the pin 130 as above described.

Thus by operating the hoist 149, all of the tubes 122 in one row laterally across the retort 30 may be pulled simultaneously from the retort. The hoist 149 is carried to that elevation above the retort 30 which will permit the tubes 122 to be entirely withdrawn from the retort and then carried forwardly of the retort 30 and lowered to have the yoke 153 come to rest within end saddles 155 and 156 carried respectively upon oppositely disposed rails 157 and 158. Upon thus positioning the yoke 153, another yoke 153 may be picked up and carried over the retort and employed to lift the next adjacent lateral row of tubes 122 therefrom and bring them over into the supporting, storage positions one after the other as determined by the spacing apart of the pairs of saddles 155 and 156 along the rails 157 and 158, Figs. 1 and 4.

Operation

Starting with the retort door 52 in the extreme forward position wherein the retort 30 is entirely

open from its under side, and also with all of the tubes 122 hanging from their respective yokes 153 forwardly of the retort 30, the first step in the operation of the retort would be to fill the groove 58 with a packing material 160 such as asbestos yarn. Also, the packing material 121 is placed in position around each opening 119 as previously indicated, following which, the motor 112 would be operated to bring the floor 52 rearwardly under the retort 30. The floor 52 is stopped in that position wherein its marginal groove 58 is in direct vertical alignment with the rib 57 depending from the under marginal face around the retort 30. The hydraulic jacks 70 are operated to raise the floor 52 to force the packing material 160 into compressive engagement around and about the ribs 57. Pressure is maintained in the jacks 70 to hold this sealing condition between the floor 52 and the retort walls.

The hoist 149 is carried over to the rearmost yoke 153 to have the block 155 engage therewith to pick up the yoke and its suspended tubes 122 to lift those tubes and carry them rearwardly over the top of the retort 30 and then lower them through the respective thimbles 118 to allow the lower ends of those tubes 122 to center and seat on the packing 121, whereupon each tube 122 is disconnected by removing the pin 130 in each instance. The hoist carries that yoke 153 back to a forward storage position for yokes only as indicated by the series of saddles 161, 162 carried on forward ends of the beams 157, 158, whereby the yokes detached from the tubes may be stored and be out of the way of travel of the following tubes to be carried over and in like manner inserted through the succeeding rows of thimbles 118 throughout the length of the retort 30 until all of the tubes 122 have been put in place. Thus in Fig. 2, the rear five rows of tubes have been positioned within the retort; while in Fig. 9, one row of tubes 122 is shown supported by their common yoke 153 in the elevated position ready to be lowered into the retort.

Now as the tubes 122 are positioned in the retort 30 as just described, the sealing of the upper ends of those tubes 122 about their lengths 126 may be effected, first by placing the packing 134 within the groove 133, forcing the plate 135 downwardly to have the lip 136 bear compressibly against that packing 134, and then forcing in the packing 139 between the tube length 126 and surrounding flange 138.

It is assumed that the material to be coked is pitch, initially liquid. Where solid particles are to be charged into the retort, such particles may be dumped through the thimbles 118 with the plate 135 removed, and after the charging operation, then these plates 135 may be installed and the sealing effected as described. Following through with the use of the pitch material, the pitch is flowed into the retort through the intake pipe 143 to any desired depth so long as there be room left within the retort over the pitch for the collection and flow of vapors and gases from the pitch to the discharge pipes 144 without overflow of the pitch when heated. In any event, the top level of the pitch will be below the shoulders about the tubes 122 from which the reduced diameter lengths 126 extend.

The burners 141 are set into operation to cause heated gases to pass upwardly through the tubes 122. The upper ends of these tubes may be left open if desired to allow the heated gases to escape into the atmosphere, but where it is desired to

11

utilize the heat of these escaping gases, the upper ends of the tube lengths 126 may be fitted with return bends 165 to conduct the combustion gases from each of those tubes 122 into a transverse collecting manifold 166, one for each two rows of tubes. Then, common ends of those manifolds 166 are interconnected into a draw-off flue 167 to carry those heated gases to the desired heat exchange destination.

The burners 141 are operated to bring the temperature of the walls of the flue tubes 122 up to that degree whereby the pitch surrounding those tubes will be heated and caused to have flow currents set up therein under boiling conditions so that the heat is not only radiated but conducted throughout the mass of the pitch.

The heat is continued to be applied through the tubes 122 until the mass of material surrounding the tubes is coked. During this primary heating period the retort is operating as a still, getting off red wax until the coked state is reached. Products of distillation will have been removed at this state as checked in the gas recovery system. Thermo-couples (not shown) are employed to determine the temperature of the mass. Now, if the process is to be carried no further, and "soft" coke is the type of coke desired, the burners 141 are shut off. The return bends 165 and their interconnecting manifolds 166, if such have been employed, are removed, or at least the return bends 165 are removed.

The hoist 149 is then employed to bring the yoke 153 successively over each lateral row of tubes 122, lowered and interconnected with those tubes and then the hoist operated to pull the tubes from the retort and carry them over to the storing positions previously indicated, one row after the other. Thus the tubes are pulled upwardly out of the mass of coke within the retort.

The retort floor 52 is then lowered by operating the jacks 70 to break the seal between it and the retort and to lower the floor from interengagement with the retort rib 57. The motor 112 is operated to pull the lowered floor forwardly from under the retort 30. Normally, the coke thereabove may drop from the retort past the rear end of the floor 52 as that floor travels forwardly. Preferably, this falling coke will fall onto a collecting dock or wharf 169 where it may be cooled to prevent combustion.

However, after the primary heating period to bring the mass to the coked state, if it is desired to produce harder and higher density coke—calcined coke—the tubes 122 are pulled from the retort and heating from the burners 141 is continued through the flues left through the coke so as to apply the heat directly to the coke to bring it up to as high as 2700° F. Then the floor 52 is pulled as before to drop the coke.

The steps of the operation may then be repeated to carry out the next coking operation. Obviously the interior of the retort 30 may be inspected for any deterioration of the walls while the floor is in the forward position, and the old packing in the various sealing positions removed and new packing installed. Obviously a battery of such retorts may be set up whereby some economy might be effected by utilizing the waste heat from the flue tubes 122 to preheat an adjacent retort. Therefore, it is to be seen that by employing the method and apparatus herein shown and described, none of the products of combustion produced by the burners 141 are allowed at any time to come into direct contact or pass through any part of the chamber directly exposed to the

12

material being coked, during the primary heating period. There is no play of flame upon the top surface of the material during this period and the heating flues through the pitch are positively defined by the flue tubes 122 removably carried by the retort.

While the invention has herein been described in the one particular form, it is obvious that many varied mechanical devices may be employed, particularly in the structural framework, the sealing means, and in the door traveling mechanism, all without departing from the spirit of the invention, and we therefore do not desire to be limited to that precise form beyond the limitations which may be imposed by the following claims.

We claim:

1. An apparatus for treating carbonaceous materials comprising in combination an apertured top and an open bottom retort; a material supporting, shiftable, bottom closing and sealing off door; a plurality of vertically positioned heating tubes detachably and sealably resting on said door and sealably extending into said retort top apertures and to be open externally of said top; means for internally heating the walls of said tubes to at least coking temperature; means for raising and lowering said door to and from its retort closing and sealing position; means for shifting said door laterally from under said retort when lowered; and means supporting said tubes from said retort top upon lowering of said floor.

2. An apparatus for treating carbonaceous materials comprising in combination an apertured top and an open bottom retort; a material supporting, shiftable, bottom closing and sealing off door; a plurality of vertically positioned heating tubes detachably and sealably resting on said door and sealably extending into said retort top apertures and to be open externally of said top; means for internally heating the walls of said tubes to at least coking temperature; means for raising and lowering said door to and from its retort closing and sealing position; means for shifting said door laterally from under said retort when lowered; and means supporting said tubes from said retort top upon lowering of said floor; said tubes being free to travel vertically in said apertures both under heat expansion and upon lowering of said door.

3. An apparatus for treating carbonaceous materials comprising in combination an apertured top and an open bottom retort; a material supporting, shiftable, bottom closing and sealing off door; a plurality of vertically positioned heating tubes detachably and sealably resting on said door and sealably extending into said retort top apertures and to be open externally of said top; means for internally heating the walls of said tubes to at least coking temperature; means for raising and lowering said door to and from its retort closing and sealing position; means for shifting said door laterally from under said retort when lowered; and means supporting said tubes from said retort top upon lowering of said floor; said apertures exceeding in diameter that of said tubes whereby said material may be charged into said retort through the apertures around said tubes before said tubes are sealed therein; said tubes supporting means comprising a projection on the tube and an abutment presented in said aperture in each instance in the path of but spaced below said projection when the tube is resting on said door.

4. An apparatus for treating carbonaceous ma-

terials comprising in combination an apertured top and an open bottom retort; a material supporting, shiftab'e, bottom closing and sealing off door; a plurality of vertically positioned heating tubes detachably and sealably resting on said door and sealably extending into said retort top apertures and to be open externally of said top; means for internally heating the walls of said tubes to at least coking temperature; means for raising and lowering said door to and from its retort closing and sealing position; means for shifting said door laterally from under said retort when lowered; and means supporting said tubes from said retort top upon lowering of said floor; a seat provided in said door for each of said tubes to interengage the lower tube end and to hold it against lateral displacement in each instance, and said tubes being maintained on their seats by reason of the weight of the tube.

5. An apparatus for treating carbonaceous materials comprising in combination an apertured top and an open bottom retort; a material supporting, shiftable, bottom closing and sealing off door, a plurality of vertically positioned heating tubes detachably and sealably resting on said door and sealably extending into said retort top apertures and to be open externally of said top; means for internally heating the walls of said tubes to at least coking temperature; means for raising and lowering said door to and from its retort closing position; means for shifting said door laterally from under said retort when lowered; and means supporting said tubes from said retort top upon lowering of said floor; a seat provided in said door for each of said tubes to interengage the lower tube end and hold it against lateral displacement in each instance, and said tubes being maintained on their seats by reason of the weight of the tube; said bottom door being flat on its upper face and sealably engaged in its closed position around its marginal edge portions of said retort, whereby upon lowering the door and shifting it laterally said door may be released from said material by a lateral shearing action to allow the material to drop by gravity and strip itself from said tubes.

6. An apparatus for coking materials comprising an open bottom retort; a shiftable door for closing the bottom of the retort; a plurality of five tubes extending through the retort in spaced relation and entirely closed off in respect to the interior of the retort and opening from respective ends exteriorly of the retort; means for heating the walls of said tubes to at least coking temperatures of said materials; and means for shifting said door to permit coked contents of the retort to drop therefrom; the top of said retort and said door being provided with vertically aligned apertures therethrough, and said tubes being vertically positioned through said top apertures to rest by lower ends on said door over the door apertures; sealing means between said tubes and said retort top and door respectively; sealing means between said door and said retort; means for centering said tubes within said retort top apertures comprising arms extending from upper end portions of the tubes; and a flared wall defining said apertures, against which said arms may initially bear.

7. An apparatus for coking carbonaceous materials comprising an open bottom retort; a shiftable door for closing the bottom of the retort; a plurality of flue tubes extending through the retort in spaced relation and entirely closed off in respect to the interior of the retort and opening

from respective ends exteriorly of the retort; means for heating the walls of said tubes to at least coking temperatures of said materials; means for shifting said door to permit coked contents of the retort to drop therefrom; the top of said retort and said door being provided with vertically aligned apertures therethrough; and said tubes being vertically positioned through said top apertures to rest by lower ends on said door over the door apertures; sealing means between said tubes and said retort top and door respectively; sealing means between said door and said retort; means for locating the upper ends of said tubes within said retort; said locating means being below the top sealing means; and means for conducting volatile matter from the upper portion of the retort.

8. For coking carbonaceous materials, a box-like retort open from its under side; a structural framework supporting said retort; a retort door carried by said framework for closing the under side of said retort; sealing means around the under marginal portion of the retort; means for raising and lowering the door into and out of sealing engagement with the retort; means for shifting the door laterally when lowered from under the retort; the ceiling of said retort being provided with a plurality of spaced passageways therethrough; said door being provided with a plurality of passageways therethrough to be axially aligned with said ceiling passageways in the closed door position; a plurality of flue tubes; means carried by said framework above said retort to lower and lift said tubes; one tube for each ceiling passageway; each of said tubes having a length such that when lowered through a ceiling passageway to have its lower end rest on said door, an upper length portion will at least extend within said ceiling passageway; means for aligning and maintaining the alignment of each tube lower end substantially axially of the door passageway; sealing means interposed between said tube lower end and said door compressibly maintained by the tube weight thereon; sealing means between said upper tube length and said retort ceiling, whereby each of said tubes affords a separate passageway entirely through but sealed off from within the retort; and means for directing a heating medium through each of said tubes to heat their walls to at least coking temperatures of said materials.

9. An apparatus for coking carbonaceous material comprising an open bottom retort; a shiftable door for closing the bottom of the retort; a plurality of flue tubes extending through the retort in spaced relation and entirely closed off in respect to the interior of the retort and opening from respective ends exteriorly of the retort; means for heating the walls of said tubes to at least coking temperatures of said materials; means for shifting said door to permit coked contents of the retort to drop therefrom; the top of said retort and said door being provided with vertically aligned apertures therethrough; and said tubes being vertically positioned through said top apertures to rest by lower ends on said door over the door apertures; sealing means between said tubes and said retort top and door respectively; sealing means between said door and said retort to render the retort capable of holding said material in its liquid state; thimbles carried in said retort top defining said apertures; said sealing means between said tubes and retort top comprising a plate in each instance encircling the tube; a channel provided around the thimble;

15

packing between the peripheral portion of the plate and said channel; and a sliding packing between the plate and the tube.

10. An apparatus for coking carbonaceous materials comprising an open bottom retort; a shiftable door for closing the bottom of the retort; a plurality of flue tubes extending through the retort in spaced relation and entirely closed off in respect to the interior of the retort and opening from respective ends exteriorly of the retort; means for heating the walls of said tubes to at least coking temperatures of said materials; means for shifting said door to permit coked contents of the retort to drop therefrom; the top of said retort and said door being provided with vertically aligned apertures therethrough; and said tubes being vertically positioned through said top apertures to rest by lower ends on said door over the door apertures; sealing means between said tubes and said retort top and door respectively; sealing means between said door and said retort; means for centering upper ends of said tubes within said retort during charging operations; thimbles carried by said retort top defining said top apertures; each of said thimbles having an upper, outwardly, funnel-like flaring portion; said retort and tube sealing means comprising sealing means of gas tight nature between the tube and the said upper thimble portion; and said tube centering means being located within said thimble below said top sealing means level.

11. An apparatus for coking carbonaceous materials comprising an open bottom retort; a shiftable door for closing the bottom of the retort; a plurality of flue tubes extending through the retort in spaced relation and entirely closed off in respect to the interior of the retort and opening from respective ends exteriorly of the retort; means for heating the walls of said tubes to at least coking temperatures of said materials; means for shifting said door to permit coked contents of the retort to drop therefrom; the top of said retort and said door being provided with vertically aligned apertures therethrough, and said

16

tubes being vertically positioned through said top apertures to rest by lower ends on said door over the door apertures; sealing means between said tubes and said retort top and door respectively; sealing means between said door and said retort; means for centering upper lengths of said tubes within said retort; thimbles carried by said retort top defining said top apertures, each of said thimbles having an upper, outwardly, funnel-like flaring portion; said retort top and tube sealing means comprising sealing means of gas tight nature between the tube and the said upper thimble portion; said tube centering means being located within said thimble below said top sealing means; 15 said tube centering means comprising a plurality of arms extending from said tube in each instance, within said thimble, the arms extending to a diameter approximately that of said upper thimble portion and greater than that of the 20 lower thimble portion.
